UNITED STATES PATENT OFFICE.

VICTOR J. GOETZ, OF PHILADELPHIA, PENNSYLVANIA.

CENTRIFUGAL REFRIGERATING-MACHINE.

1,253,026.

Specification of Letters Patent.

Patented Jan. 8, 1918.

Application filed June 10, 1915. Serial No. 33,250.

To all whom it may concern:

Be it known that I, VICTOR J. GOETZ, a citizen of the United States, residing in the city and county of Philadelphia, State of Pennsylvania, have invented a new and useful Centrifugal Refrigerating-Machine, of which the following is a specification.

In refrigerating machines applicable for any purposes and particularly for household purposes, it is desirable to eliminate any and all complications such as, for example, the adjusting of valves, the tightening of stuffing boxes, the frequent oiling of the moving parts, the necessity of keeping close watch of the different gages, and other mechanical adjustments which are beyond the skill of a layman. It is also essential that the machine is constructed in such a manner that it is perfectly safe to operate and free from any possibility of the escape of suffocating fumes, and that the machine will operate with a minimum of vibration and noise.

With the above and other objects in view which will hereinafter more clearly appear my invention in its broad and generic scope consists of a centrifugal refrigerating machine.

It further consists of a novel refrigerating machine wherein the moving parts are all inclosed, and wherein high pressure and low pressure chambers are provided which are constructed in a novel manner.

It further consists of a novel refrigerating machine wherein the compressing medium also serves to lubricate the bearings.

It further consists of a novel refrigerating machine wherein high and low pressure chambers are formed by means of an outer rotatable casing and an inner stationary member, novel means being provided for the passage of the compressing medium and the refrigerating medium, and novel means being also provided to automatically control the pressure in the expansion chamber of the machine.

Other novel features of construction and advantage will hereinafter more clearly appear in the detailed description of the invention.

For the purpose of illustrating my invention, I have shown herein a typical embodiment which illustrates the principle thereof and which will give satisfactory and reliable results in practice, although it is of course

to be understood that the various instrumentalities of which my invention consists can be variously arranged and organized and that my invention is not limited to the precise arrangement and organization of these instrumentalities as herein set forth.

Figure 1 represents a sectional elevation of a centrifugal refrigerating apparatus, embodying my invention.

Figs. 2 and 3 represent, respectively, on an enlarged scale, sectional elevations of portions of the machine.

Similar numerals of reference indicate corresponding parts in the figures.

Referring to the drawings:

The refrigerating medium employed may be any of the well known refrigerants such as, for example, ammonia, ethyl chlorid and the like, but for convenience of description I have assumed that anhydrous ammonia is used. The compression medium employed may be any of the well known compressing fluids such as, for example, mercury, oil or the like, but for convenience of description, I refer to mercury as being employed to carry the refrigerant from the low pressure chamber in the form of a gas to the high pressure chamber in a proper condition for liquefying. The aspirating action on the ammonia gas is effected by the passage of mercury past the nozzle, the mercury being actuated by centrifugal force.

1 designates the base or supporting framework, on which is mounted a water tank 2 and a brine tank 3. Bearings 4 are provided in which are journaled a rotatable shell or casing 5, portions of which rotate within the water tank and within the brine tank. The outer casing 5 comprises a tubular cylindrical portion 6, which terminates in a cup-shaped flange 7 at one end, and an end closure or plate 8 is secured thereto by means of the fastening devices 9. The plate 8 has connected therewith a chambered hub 10 to which is secured in any desired manner a connection from the prime mover, and for purpose of illustration I have shown a pulley 11 adapted to receive a belt driven by any desired source of power. I preferably employ a directly connected motor in order to eliminate the vibration and noise, which might otherwise occur.

The cup-shaped flange 7 and closure 8 revolve within the water tank 2 and form with an inner stationary member 12 a com-

pression chamber 13. The stationary member 12 comprises a plate or disk 14 having laterally extending flanges 15 the inner faces of which are threaded, in the present instance, in order to receive a disk 16 the lower portion of which is preferably solid or weighted, while the upper portion thereof is chambered, as at 17, in order that the member 12 will at all times assume a stationary position within the revolving casing 5.

The disk 16 is in the form of an annulus having its inner portion forming an enlarged rounded head 18 and the inner face of the end closure 8 is shaped to provide a chamber or passage 19. The central portion of the plate 8 is curved inwardly to form the apex 20. The disk 16 and the plate 14 are connected in such a manner that a chamber 21 is formed between such parts. 22 20 designates a nozzle connected with the central portion of the plate 14 and the outer face of said nozzle, as at 23, is concentric with the contiguous walls of the member 18, as will be best understood by reference 25 to Fig. 3. The nozzle 22 communicates by means of a passage 24, extending through a hub 25 of the plate 14, with a chamber 26 of a conduit 27 which latter is connected with said hub 25 in any desired manner. In 30 the present instance, the conduit 27 is in threaded engagement with said hub 25 and serves to retain in position a race of the ball bearing 28. A fastening device 29 is preferably provided to prevent relative movement 35 of the parts. The chamber 26 is in communication with the chamber 21 by means of a restricted passage 30 extending through the hub 25. The chamber 21 is also in communication with a chamber 31, formed between 40 the plate 14 and the wall of the flange 7, by means of a desired number of ports 32 extending through the plate 14 at its outer periphery.

33 designates a passage communicating 45 with the compression chamber 13 near its upper end and extending through the disk 16 and the plate 14 and said passage 33 communicates by means of a restricted passage 34 with a pipe 35, one end of which is connected to the hub 25. 36 designates a removable plug carried by the plate 14. 37 designates a closure at one end of the conduit 27 with which the tube 35 is in threaded engagement, said tube communicating with a 55 port 38, see Fig. 2, which leads to a valve seat 39 controlled by the valve 40 which is illustrated as having a working fit in the passage 41 which opens into the expansion chamber 42. A passage 43 is also provided 60 leading from the passage 41 and opening into the expansion chamber 42. The closure 37 is provided with a passage 44 through which the mercury may pass from the chamber 26 into the expansion chamber 42. An 65 upper passageway 45 is also provided. 46

designates an antifriction or ball bearing similar to the ball bearing 28 a portion of which is carried by the conduit 27 and a portion by the casing 5, which latter is provided with an outwardly extending flange or plate 70 47, to the outer periphery of which is connected a bell or other shaped casing 48 by means of fastening devices 49.

50 designates a plate or disk the upper portion of which is chambered, as at 51, and 75 this plate or disk is mounted on the conduit 27 in any desired manner, and in the construction shown is illustrated as being connected therewith by means of a key 52 and a nut 53, which is in threaded engagement 80 with the conduit 27, see more particularly Fig. 2. One of the bearing rings of the ball bearing 46 is connected to the plate 50 by means of fastening devices 54. In order to provide for the lubrication of the ball bearing 46, I form a passage 55 leading from the bottom of the plate or disk 50 to the ball bearing 46.

The valve 40 is automatically controlled and, in the form illustrated, it is in threaded engagement with a cross bar 56 and is provided with a nut 57. The cross bar 56 is carried by the guide rods 58 and is adjustably connected with said guide rods owing to the provision of the nuts 59 on opposite sides 95 of the cross bar. The rods 58 are guided in a bracket 60 which is fixed in any desired manner with respect to the plate 50 and the outer ends of said guide rods 58 are adjustably connected with a cross bar 61 by means 100 of nuts 62. The cross bar 61 has adjustably connected therewith by means of nuts 63, a rod 64, which is secured in any desired manner to a diaphragm, 65, said diaphragm being retained in position by means of the 105 plate 66 connected in any desired manner to the bracket 60 and adapted to secure in fixed position the outer periphery of the diaphragm. The bracket 60 has the central portion thereof inwardly deflected to form a 110 chamber in which is located a spring 67 which normally maintains the diaphragm in neutral position.

68 designates a guide bushing for the rod 64 and an adjusting device for the tension 115 of the spring 67, said bushing being adjustably carried by the bracket 60. 69 designates a cover plate secured to the bracket 60 by means of fastening devices 70 and said plate can be readily removed when it is desired to adjust the tension of the spring 67, 120 which can be accomplished by rotating in the proper direction the bushing 68.

In order that the pressure in the expansion chamber may be readily determined, I 125 provide means to receive a gage connection. 71 designates a port leading from the expansion chamber 42 and communicating with a chamber 72 into which the reduced end of a coupling valve 73 extends, the end of said 130

valve being adapted to close said port 71. 74 designates a passage through the coupling valve 73. 75 designates a stuffing box. The compression chamber 13 is also adapted to have a gage connected therewith. I provide ports 76 leading from the compression chamber 13 to a chamber 77 into which extends a coupling valve 78 having a passage 79 therethrough, said valve being provided with a stuffing box 80.

The operation of my novel centrifugal refrigerating machine will now be readily apparent to those skilled in this art and is as follows:—

15 The pressure at the compression end of the machine is determined by the temperature and quantity of water in the water tank 2, and will be about 180 pounds in midsummer or, in other words, will substantially 20 correspond to any other compression refrigerating plant using anhydrous ammonia as its refrigerating medium.

Assuming that the machine is at rest, and the pressure equalized on both sides of the 25 machine and that the valve 40 is closed, the compressing medium, such as mercury, will lie in the bottom of the compression chamber 13 and substantially an equal amount will be on each side of the stationary disk 30 in the channels 19 and 31 and also in the chamber 21. A small quantity of mercury will also be in the expansion chamber 42. The liquid ammonia will lie on top of the mercury and some of it will also be in the 35 expansion end and the ammonia gas will occupy the remaining space within the casing 5. The casing 5 is now revolved in any desired manner and during such revolution the disks or members 16 and 50 and their 40 adjuncts remain stationary. As soon as the casing 5 revolves, the mercury will fly to the outside due to centrifugal force and as it passes the small holes 32, due to the fact that the members 12 and 16 are stationary, the 45 mercury will enter into the channel 21 and be forced at a high rate of speed through the small contracted opening 81 thereby aspirating the ammonia gas through the nozzle 22 into the channel 19. Since the ammonia 50 gas is being crowded into a smaller space the compression of the gas naturally follows, and since the entire compression end of the machine revolves in water the latent heat will be carried off to convert this ammonia 55 gas into a liquid. As the pressure in the chamber 19 becomes greater, and the pressure in the chamber 31 correspondingly decreases, the revolving mercury will be forced over from the chamber 19 to the chamber 31 60 until the centrifugal force of the mercury on the one side balances the pressure and the centrifugal force of the liquid on the other side, thus forming a seal between the high and low side or, in other words, a liquid 65 stuffing box is provided. This transfer of

the ammonia gas from the expansion end of the expansion chamber continues until the pressure in the expansion chamber 42 has lowered to the point at which the valve 40 is set which for purpose of illustration 70 we may assume to be twenty pounds above atmospheric. When the spring 67 overcomes the pressure on the diaphragm 65 and causes the diaphragm rod 64 to move outwardly, the cross bar 61, guide rods 58 75 and cross bar 56 will also be moved outwardly thereby opening the valve 40 and permitting the ammonia liquid to pass from the compression chamber 13 through the passage 33, through passage 34, through conduit 35, through port 38 and passage 43 into the expansion chamber 42. This ammonia liquid at once expands into a gas, thus lowering its temperature and tending to raise the pressure in the expansion chamber 42. As 80 soon as the pressure expands sufficiently in the chamber 42, the valve 40 will again close to prevent any more ammonia liquid from being carried over. The pressure is then lowered in the expansion chamber 42 until 85 the valve 40 again opens to admit more liquid or the valve 40 remains open to permit as much liquid into the expansion chamber as the compression chamber can carry off and maintains an even pressure at the expansion end. The passage 30 is constantly 90 open to let a small quantity of mercury flow continuously into the chamber 26 and through passage 44 into the expansion chamber for the purpose of lubrication. 95

The mercury with its ammonia gas jetting into the channel 81 is so intimately mixed as to form substantially a vapor. The heat of the gas is therefore evenly and rapidly given up to the mercury which in turn 105 gives up its heat to the interior wall of the compression end of the casing 5, which is continually coming into contact with the cold water, so that the compression end of the casing 5 also becomes a condenser. The 110 small particles into which the mercury is broken up when it is injected into the compression chamber will quickly separate from the gas and the liquid ammonia due to the great difference in their respective weights, 115 and the mercury will thus be carried to the outside and pass over the small space left between the disk consisting of the members 14 and 16 to join the solid body of mercury on the other side of the disk in the channel 120 31, only to return again through the holes 32 to continue the cycle of the operation.

It will be noted that the inner face of the tubular portion 6 of the rotatable casing 5 is preferably made slightly conical in 125 shape, the greater diameter being toward the compression end so that the returning mercury will travel toward the compression end due to centrifugal force.

The entire apparatus is so proportioned 130

that when the machine is working at its proper pressures, the mercury will just fill the channels or chambers 21 and 31 while the liquid ammonia will fill about two-thirds of the channel or chamber 19. The valve couplings 73 and 78 are for the purpose of connecting gages to ascertain the pressures when assembling and adjusting the machine, and one of these valves is also employed to exhaust the air from the apparatus and fill it with ammonia. It will be seen that the ammonia gas passes from the expansion chamber 42 through passage 45 into the chamber 26 and thence through passage 24 to and through the nozzle 22.

Special attention is directed to the fact that owing to the novel manner of constructing the rotatable casing there can be no leakage of the refrigerating or compressing medium and a mercury seal is formed between the high pressure and the low pressure chambers.

Since the casing is rotatably mounted, I eliminate the necessity of employing stuffing boxes and I have also reduced the number of frictional parts to a minimum with consequent increase in the durability of the construction.

While I preferably provide a restricted passage 30 and a passage 44 in order that the mercury will serve to lubricate the ball bearing, it will be apparent that these passages may be omitted without departing from the spirit or scope of my invention. The mercury in the expansion chamber 42 works upwardly through the passage 55 around the anti-friction devices of the ball bearing 46 and owing to centrifugal force the mercury is carried to and through the ball bearing 28. It will be understood that the tank 3 may simply form an air chamber of the refrigerator or it may be filled with brine which may be circulated in any desired manner and in the form shown the circulation will be effected by the rapid revolution of the casing 48.

In so far as I am aware, I am the first in the art to devise a centrifugal refrigerating machine in which a refrigerating medium, such as mercury, produces, due to centrifugal force, an aspirating action on the ammonia gas, or to devise a machine in which the mercury forms a seal between the high and low pressure chambers and it is therefore to be understood that my claims to such features are to receive the broad and generic interpretation to which a pioneer invention is entitled.

It will now be apparent that I have devised a novel and useful construction of a centrifugal refrigerating machine which embodies the features of advantage enumerated as desirable in the statement of the invention and the above description, and while I have, in the present instance, shown and described

a preferred embodiment thereof which will give in practice satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. A centrifugal refrigerating machine, having intercommunicating high and low pressure chambers to receive the refrigerating and the compressing mediums, and an aspirator operated by centrifugal force on the compressing medium to continuously aspirate the gaseous portion of the refrigerating medium from the low pressure chamber to the high pressure chamber and change it to a liquid.

2. A centrifugal refrigerating machine, having intercommunicating high and low pressure chambers to receive the refrigerating and the compressing mediums, and an aspirator operated by centrifugal force on the compressing medium to continuously aspirate the gaseous portion of the refrigerating medium from the low pressure chamber to the high pressure chamber and change it to a liquid, and means to automatically control the passage of such liquid to the low pressure chamber.

3. A centrifugal refrigerating machine, having intercommunicating high and low pressure chambers to receive the refrigerating and the compressing mediums, and an aspirator operated by centrifugal force on the compressing medium to continuously aspirate the gaseous portion of the refrigerating medium from the low pressure chamber to the high pressure chamber and change it to a liquid, and means controlled by the pressure in said low pressure chamber to control the passage of such liquid to the low pressure chamber.

4. A centrifugal refrigerating machine, comprising a rotatable casing having a compression chamber at one end and an expansion chamber at the other end, a passage for liquid refrigerant leading from said compression chamber to said expansion chamber, and an aspirator operated by centrifugal force on the compressing medium to effect the continuous travel of gaseous refrigerant from the expansion chamber to said compression chamber.

5. A centrifugal refrigerating machine, comprising a rotatable casing having a compression chamber at one end and an expansion chamber at the other end, a passage for liquid refrigerant leading from the upper end of said compression chamber to said expansion chamber, means to automatically control said passage, and an aspirator operated by centrifugal force on the compressing

- medium to effect the continuous travel of gaseous refrigerant from the expansion chamber to said compression chamber.
6. A centrifugal refrigerating machine, comprising a rotatable casing having a compression chamber and an expansion chamber, a stationary member within said casing having a passage therethrough communicating with said chambers, the portion of said member within said compression chamber having ports in its side communicating with a chamber terminating in proximity to said passage, an aspirator, means to rotate said casing to cause centrifugal force to effect the continuous travel of the compressing medium through said ports to aspirate the gaseous refrigerant through said passage, means to cool said compression chamber, and means to control passage of liquid refrigerant to said expansion chamber.
7. A centrifugal refrigerating machine, comprising a rotatable casing having a compression chamber and an expansion chamber, a stationary member within said casing having a passage therethrough communicating with said chambers, the portion of said member within said compression chamber having ports in its side communicating with a chamber terminating in proximity to said passage, an aspirator, means to rotate said casing to cause centrifugal force to effect the continuous travel of the compressing medium through said ports to aspirate the gaseous refrigerant through said passage, means to cool said compression chamber, and means to control passage of liquid refrigerant through said stationary member to said expansion chamber.
8. A centrifugal refrigerating machine, comprising a water tank, a chamber to be cooled, a casing having a compression chamber located within said tank and an expansion chamber located in the chamber to be cooled, a stationary member within said chambers and having a disk within the compression chamber with ports near its outer periphery, an annulus spaced from said disk and having its inner portion rounded and its outer portion connected to said disk, a nozzle communicating with the expansion chamber and projecting into the compression chamber in proximity to the rounded portions of said disk, means to rotate the casing to cause the centrifugal action on the compressing medium to effect passage of the refrigerating medium through said nozzle, and means to control the passage of refrigerant from the compression chamber to the expansion chamber.
9. A centrifugal refrigerating machine, comprising a cooling tank, a chamber to be cooled, a casing having a compression chamber in said tank and an expansion chamber in the chamber to be cooled, an inner stationary member, antifriction devices between
- said member and casing, said member comprising a plate with ports through its side, a disk spaced from the plate to form a channel and connected to its outer portion, said disk having a central passage therethrough, a nozzle discharging into said passage and communicating with said expansion chamber, said member having a passage communicating with the upper portion of said compression chamber and with said expansion chamber, an automatically controlled valve for said last named passage, and means to rotate said casing.
10. A centrifugal refrigerating machine, comprising a rotatable casing, an inner stationary member, antifriction devices between said casing and member, and means to pass the compressing medium to said bearings to effect the lubrication thereof.
11. A centrifugal refrigerating machine, comprising a closed casing having intercommunicating compression and refrigerating chambers, valves controlling communication with said chambers, an aspirator, means to rotate said casing to effect through centrifugal action on the compressing medium the continuous passage of gaseous refrigerant to the compression chamber, and means to pass liquid refrigerant from the compression chamber to the expansion chamber.
12. A centrifugal refrigerating machine, comprising a casing having compression and expansion chambers connected by a tubular connection, a disk in the compression chamber, an annulus having its lower portion weighted and its outer portion connected with said disk and forming therewith a channel communicating with ports through the disk, a nozzle carried by the disk, a conduit connected with the disk and communicating with said nozzle, a closure for said conduit having a passage leading from the expansion chamber into said conduit and a port communicating with said expansion chamber, a second disk carried by said conduit, a pressure controlled valve carried by said second disk and controlling said port, a tube communicating with said port and with a passage opening through said first disk and annulus at their upper portions, and means to rotate said casing.
13. A centrifugal refrigerating machine, comprising a casing having compression and expansion chambers connected by a tubular connection, a disk in the compression chamber, an annulus having its lower portion weighted and its outer portion connected with said disk and forming therewith a channel communicating with ports through the disk, a nozzle carried by the disk, a conduit connected with the disk and communicating with said nozzle, said tubular connection and conduit forming a conical space with its greatest diameter toward the compression chamber, antifriction devices between said

casing and conduit, a closure for said conduit having a passage leading from the expansion chamber into said conduit, and a port communicating with said expansion chamber, a 5 second disk carried by said conduit, a pressure controlled valve carried by said second disk and controlling said port, a tube communicating with said port and with a passage opening through said first disk and 10 annulus at their upper portions, and means to rotate said casing.

14. A centrifugal refrigerating machine, comprising a casing having compression and expansion chambers connected by a tubular 15 connection, a disk in the compression chamber, an annulus having its lower portion weighted and its outer portion connected with said disk and forming therewith a channel communicating with ports through 20 the disk, a nozzle carried by the disk, a conduit connected with the disk and communicating with said nozzle, a closure for said conduit having a plurality of passages leading from the expansion chamber into said 25 conduit and a port communicating with said expansion chamber, said disk having a passage therethrough communicating with said channel and said conduit, a second disk carried by said conduit, a pressure controlled 30 valve carried by said second disk and controlling said port, a tube communicating with said port and with a passage opening through said first disk and annulus at their upper portions, and means to rotate said 35 casing.

15. A centrifugal refrigerating machine, comprising a casing having compression and expansion chambers connected by a tubular connection, a disk in the compression chamber, an annulus having its lower portion weighted and its outer portion connected with said disk and forming therewith a channel communicating with ports through 40 the disk, a nozzle carried by the disk, a conduit connected with the disk and communicating with said nozzle, a closure for said conduit having a plurality of passages leading from the expansion chamber into said conduit and a port communicating with said 45 expansion chamber, said disk having a passage therethrough communicating with said channel and said conduit, a second disk carried by said conduit, an antifriction bearing between said conduit and casing, said second 50 disk having a passage from its lower portion to said antifriction bearing, a pressure controlled valve carried by said second disk and controlling said port, a tube communicating with said port and with a passage 55 opening through said first disk and annulus at their upper portions, and means to rotate said casing.

16. A centrifugal refrigerating machine, having intercommunicating high and low 60 pressure chambers to receive the refrigerat-

ing and the compressing mediums, and means to aspirate the gaseous portion of the refrigerating medium from the low pressure chamber to the high pressure chamber.

17. A centrifugal refrigerating machine 70 having high and low pressure chambers to receive the refrigerating and condensing mediums, an aspirator communicating with said chambers, and means for causing the condensing medium to draw the refrigerating medium through said aspirator from the low pressure chamber to the high pressure chamber. 75

18. A centrifugal refrigerating machine comprising a rotatable casing having a compression chamber and an expansion chamber, an aspirator nozzle in communication with said chambers, and a stationary member within said casing and having a passage therethrough from a point near the periphery of the casing to the surface of said nozzle. 80

19. A centrifugal refrigerating machine comprising a rotatable casing having a compression chamber and an expansion chamber, an aspirator comprising a nozzle concentrically located and in communication with said chamber, and a restricted passage surrounding said nozzle, and a stationary member within said casing having a passage 90 therethrough extending from said restricted passage to a point farther from the axis of the casing. 95

20. A centrifugal refrigerating machine comprising a rotatable casing, an inner stationary member, antifriction devices between said casing and member, and passages through said stationary member to permit the compressing medium to pass to said devices to lubricate them. 100

21. A centrifugal refrigerating machine comprising a rotatable casing having a compression chamber at one end and an expansion chamber at the other end, a passage for liquid refrigerant leading from said compression chamber to said expansion chamber, means to automatically control said passage, an aspirator, and means operated by centrifugal force on the compressing medium to effect the continuous travel of 110 gaseous refrigerant from the expansion chamber to said compression chamber. 115

22. A centrifugal refrigerating machine, comprising a casing rotatably mounted and having high and lower pressure chambers, 120 a stationary member within said casing having a passage therearound communicating with said chambers, a compressing medium and a refrigerating medium, said compressing medium serving to seal said passage. 125

23. A centrifugal refrigerating machine having intercommunicating compression and expansion chambers to receive the refrigerating and the compressing mediums and operated by centrifugal force on the compress- 130

ing medium to continuously aspirate the gaseous portion of the refrigerating medium into the compression chamber, and means to permit the compressing medium to pass from said compression chamber into said expansion chamber, and the compressing medium traveling from the expansion cham-

ber to the compression chamber due to the action of centrifugal force.
